MACHINE FOR COATING WAFERS

John R. Brandt, Chicago, Ill., assignor to Salerno
Machinery Company, Chicago, Ill., a corpora-
tion of Illinois

Application June 6, 1951, Serial No. 230,210

6 Claims. (Cl. 107—27.)

1

This application is a continuation-in-part of my copending application S. N. 47,463, filed September 2, 1948, now U. S. Patent Number 2,563,813, issued August 14, 1951.

This invention relates to a machine for coating wafers or flat cakes, and more particularly to a novel hopper control mechanism for use with a hopper adapted to slide over stencil openings during application of a confectionery coating to a wafer or cake.

The invention involves improvements in the type of machine disclosed in Patent No. 1,570,405 granted January 19, 1926, to Ferdinando G. Salerno, and more particularly the invention comprises an improvement in the hopper control and actuating mechanism disclosed in my copending application S. N. 47,463, filed September 2, 1948, now U. S. Patent Number 2,563,813. The machine to which my improvements relate is in the general class adapted for large scale production of sandwich cookies or cakes of the type comprising a confection material such as chocolate or sugar icing interposed between a pair of top and bottom wafers.

The slidable coating hopper disclosed in said Salerno patent, and also utilized in other similar machines, was adapted to be filled with a confection material which was fed from the bottom thereof and forced through stencil openings in a stencil box onto the upper surfaces of a plurality of wafers. The bottom of the hopper was open at all times and was provided with relatively broad flat bearing surfaces which slidably engaged the upper surface of the stencil plate for reciprocal movement thereover. The plane of the bottom bearing surfaces of the hopper remained parallel with the upper surface of the stencil plate at all times during reciprocation.

While this construction was relatively satisfactory in general operation, it nevertheless required constant attention in that after a relatively few reciprocations over the stencil plate, a quantity of the coating material became smeared in a thick layer over the stencil plate and piled up at either end of the stencil box at the end of the hopper strokes. This caused the hopper to be raised off the stencil plate so that the coating was not cleanly applied to the wafer and was considerably thicker than that desired and determined by the thickness of the stencil plate. Moreover, the coating material, which was of relatively thick plastic consistency, as it increased in quantity and thickness on the stencil plate tended to retard machine operation and often was forced over the upstanding marginal

walls of the stencil box and spilled onto the machine parts, the conveyor belt, and the wafers themselves.

As a result, it was necessary to shut down the entire machine at frequent intervals to clean off the surface of the stencil plate and the walls of the stencil box, which stoppage, multiplied by the number of times required therefor during a working day, necessarily reduced to a considerable extent the daily machine output. Furthermore, an operator was required to maintain a constant vigil adjacent the hopper and stencil box so that the condition could be revealed before it was built up to an extreme, thus increasing labor costs and the ultimate cost of the finished product.

In the invention described in my copending application S. N. 47,463, now U. S. Patent Number 2,563,813, the aforementioned difficulties are overcome by means of a novel hopper and operating mechanism which permit the hopper to be reciprocated across the stencil plate while at the same time being tilted so that the bottom edges of the hopper serve as scraping edges to keep the stencil plate clean. The hopper tilts or rocks in alternate directions as it moves back and forth across the stencil plate, and substantially the entire weight of the hopper is borne by the stencil plate as the scraping edges of the hopper engage the stencil plate in intimate line bearing contact therewith.

Although the mechanism described and claimed in my above-mentioned copending application constitutes a vast improvement in coating machines of the type here involved, nevertheless, I have found that there are certain disadvantages in permitting the entire weight of the hopper to be disposed against the stencil plate during the reciprocating scraping movement of the hopper. The primary disadvantage in this respect is that the stencil plate tends to wear through too quickly because of the repeated abrasive scraping action of the hopper. I have now discovered a means of mounting and actuating the reciprocable rockable hopper so that there is no undue wear on the stencil plate while at the same time realizing all of the advantageous operating features of my previous invention.

Accordingly, a primary object of the invention is to provide, in a coating machine of the type described, a novel and improved hopper adapted to reciprocate in slidable contact with a stencil plate and through the open bottom of which the confection coating may be fed through stencil

openings without smearing or spreading over the surface of the stencil plate.

A further object of the invention is to provide an improved hopper support and actuating mechanism for a coating machine of the type described whereby combined reciprocating and rocking movement of the hopper is effected without excessive wear on the stencil plate.

Other objects and advantages of the invention will become apparent as this description progresses, reference being had to the accompanying drawings in which:

Fig. 1 is a side elevational view of a machine for coating wafers to which one embodiment of the improved hopper control mechanism comprising my invention has been applied;

Fig. 2 is an enlarged fragmentary view partly in section and illustrating the operating positions of the hopper and associated elements of the machine;

Fig. 3 is a fragmentary top plan view of the hopper and the front or feed end of the machine; and

Fig. 4 is a fragmentary longitudinal sectional view of the hopper showing its position relative to the die or stencil plate as it slides thereover to apply a confection coating on a wafer therebelow.

By reference to Fig. 1 of the drawings, it will be seen that the wafer coating machine to which the hopper control mechanism of the present invention has been applied comprises generally a supporting frame structure having vertical, longitudinally extending plates 10 and a plurality of cross pieces or braces, some of which will be referred to specifically hereinafter. As will hereinafter be described in detail, the various operating shafts of the machine are supported between these side plates 10. At the top of the frame structure there is supported an intermittently movable conveyor belt 11 which extends from the front or feed end of the machine (the left end as viewed in Fig. 1) to the rear or delivery end thereof (the right end as seen in Fig. 1). The wafers are fed onto the moving conveyor belt 10 by a feeding mechanism, indicated generally by the numeral 12, and they then pass under the improved hopper and stencil mechanism, indicated generally by the numeral 13, where they are coated with an icing or similar confection material. The belt 11 is stationary during the stenciling operation.

After receiving the confection coating, the wafers then pass under a second wafer feeding mechanism, indicated generally by the numeral 14, from which top wafers are positioned down onto the coating. Thus there are formed composite cookies of the sandwich type comprising top and bottom wafers with the confection material therebetween. The completed sandwich cookies thereafter pass from the machine to a loading area in which they are removed from the conveyor and placed in containers.

The belt 11, as shown best in Fig. 1, is endless in construction, and at its left end it extends around and is supported by a drum 16 and at its right end it extends around a smaller drum or roller (not shown). Intermittent movement of the drum 16 is effected by means of a ratchet wheel 17 loosely mounted on a cross rock shaft 18 and secured to the drum 16, the drum 16 also being supported on the shaft 18 for rotative movement relative thereto. The ratchet wheel 17 is engaged by a pawl 19 pivoted to the upper end of a short arm 20 fixed to the cross shaft 18

and extending upwardly at a forty-five degree angle therefrom. Depending from and fixed to the cross shaft 18 is another short arm 21, the lower end of which is pivotally connected to the upper end of a pitman rod 22. The rod 22 is eccentrically mounted on a continuously rotating shaft 23 so that through the rod 22 and the arm 21, the arm 20 is rocked from left to right causing the pawl 19 to intermittently rotate the drum 16 and advance the belt 11 to the right in a stepwise manner.

Although not shown in the drawings, it will be understood that the shaft 23, which is the main driving shaft of the machine, extends transversely of the machine and is supported at its ends in suitable bearings secured in the side plates 10. Rotation of the shaft 23 is effected by a sprocket and chain drive (not shown) which extends to the rear of the machine and is operably connected through suitable driving connections to a source of power such as an electric motor (not shown). A manual clutch lever 24 is provided for regulating a clutch mechanism connecting the main drive shaft 23 with the power source.

The cookie feeding mechanism 12 is also operated off the shaft 23 as seen best in Fig. 1. A horizontal rod 29 has its right end eccentrically secured to the shaft 23 and its forward end adjustably and pivotally connected by a pin and slot connection to the lower end of a rocking lever 30. The lever 30 is pivotally mounted intermediate its ends on a short cross shaft 31 supported in the machine frame and its upper end is pivoted to the rear end of a short link 32 secured to the rear end of a reciprocable slide 33. Above the slide 33 there is supported a wafer magazine 34 comprising a plurality of vertical chutes adapted to receive a plurality of pre-baked wafers in stacked relation which feed downwardly by gravity onto a table 35 over which the slide 33 reciprocates. The magazine 34 is spaced above the table 35 a distance slightly greater than the thickness of the wafer to permit one wafer at a time to drop below each of the chutes. The slide 33 is slightly less in thickness than the thickness of the wafer and its right or rearward edge is adapted to engage the plurality of wafers and to push them off the table 35 onto the belt 11. When the slide 33 is retracted to the left, another group of wafers drop down onto the table 35 and they in turn are also forced onto the belt as the slide is again moved to the right.

As the belt 11 thereafter moves intermittently to the right, the wafers are moved under a flat horizontal stencil plate 37 (Figs. 2 and 4) having a plurality of transversely aligned openings 38 therethrough. The plate 37 is removably supported in a rectangular stencil box 37a having upright walls 39 and a bottom 40 with an enlarged space or opening 40a, the plate 37 resting on the bottom 40 and the openings 38 being superimposed over the space 40a. An elongated hopper 41 is slidably supported above the stencil plate 37 for reciprocal scraping movement over the top surface thereof and is adapted to be filled with a quantity of confection material of a rather high viscosity. The hopper 41 which is open at both its top and bottom is formed by side walls 42 and vertical end walls 43. The side walls 42 taper downwardly and inwardly toward each other to form a throat a short distance above the stencil plate at which point the walls 42 taper outwardly in the reverse direction to provide a flared bottom.

As the hopper reciprocates it moves from one

side of the stencil box to the other passing over the openings 38 on each stroke, the openings conforming to the shape of the wafer but being slightly less than the diameter thereof. When the hopper 41 passes over the openings 38 a quantity of the coating material is forced down within each opening 38 and onto the top surface of the wafer which is held in raised position up against the under surface of the stencil plate 37 by a mechanism to be described presently. As shown in Fig. 4, the thickness of the stencil plate 37 determines the thickness of the coating, indicated at 44, which is applied to a wafer 46.

The hopper 41 is rockably supported relative to the stencil plate 37, in a manner to be described presently, in order that only one of the side walls 42 thereof will contact the stencil plate 37 during sliding scraping movement and the other side wall will be slightly raised therefrom. By such a construction the bearing engagement of the hopper 41 with the stencil plate 37 will be restricted to a knife edge or line contact and the confection material does not have sufficient body to hold the hopper out of such contact. Consequently, as the hopper 41 slides over the plate, it scrapes clean the upper surface of the plate and prevents the coating material from working its way out over the stencil plate surface and from forming large masses at the ends of the hopper strokes. The rocking movement of the hopper 41 occurs at the end of each stroke so that the hopper slides first in one direction on one line edge of the bottom of one side wall 42 and then in the other direction on the line edge of the bottom of the opposite side wall 42.

The mechanism for causing reciprocal sliding and rocking movement of the hopper 41, as shown in Figs. 2 and 3, comprises a pair of horizontally disposed bars or slides 47 slidably supported adjacent each end wall 43 of the hopper in grooved horizontal guides 45 secured to the frame of the machine. The slides 47 are held down within the guides 45 by retaining plates 48 secured to the top surfaces of the guides 45. An upstanding bracket 49 is secured to each of the slides 47, each of the brackets extending angularly and rearwardly to provide a pair of offset supporting yokes 51 at the upper ends thereof. The hopper 41 is rockably supported on the brackets 49 by means of a pair of pivot pins 52 extending rigidly from the upper portions of the hopper end walls 43 into the yokes 51. For regulating the elevation of the hopper 41 above the stencil plate 37, each of the pivot pins 52 is provided with a diametrically extending adjusting screw 53 which seats in the yoke 51 of the corresponding bracket 49. Each screw 53 has a lock nut 54 for retaining the screw in adjusted position.

It will readily be seen that by adjusting the screws 53 the degree of clearance or contact between the bottom of the hopper 41 and the stencil plate 37 can be closely controlled and consequently the pressure or load on the stencil plate need not become excessive. Limited pivotal or rocking movement of the hopper 41 is easily effected, as hereinafter described, because of the pivotal relation of the screws 53 to the yokes 51. By reason of the adjustment provided by the screws 53 the entire weight of the hopper 41 need not be exerted on the stencil plate 37 and, in practice, the screws 53 may be regulated to provide a minimum effective scraping pressure during reciprocation of the hopper 41 across the plate. As the plate 37 tends to wear or abrade with continued use, the screws 53 can be adjusted to

maintain the proper degree of scraping contact and pressure. In addition, the plate 37 which rests on the bottom 40 of the stencil box may be readily removed and replaced when wear becomes excessive.

Actuation of the slides 47 is accomplished by means of a pair of reciprocating elongated arms 56 extending forwardly and provided with downwardly curved front ends which are pivotally connected to the hopper 41 by a pair of pins or studs 57 extending rigidly from the lower portions of the hopper end walls 43 through apertures in the arms 56. The arms 56 are caused to reciprocate longitudinally by upright rocker arms 58 pivotally connected at their upper ends to the rear ends of the arms 56. Although not shown in the drawings, the rocker arms 58 are mounted on a rock shaft and are moved back and forth by a suitable cam arrangement and operating connections with the main drive shaft 23. The details of the driving and operating mechanism by which the rocker arms 58 are operated form no part of the present invention and reference is made to my copending application S. N. 47,463, now U. S. Patent Number 2,563,813, for a complete description thereof.

As the arms 56 reciprocate in opposite directions, the pins 57 are moved into coacting engagement with the rear edges of the brackets 49 in one direction of movement and with a pair of blocks 59 in the opposite direction of movement, the blocks 59 being rigidly mounted on the slides 47 in rearwardly spaced relation with respect to the brackets 49. Thus, reciprocating movement of the arms 56 is transmitted to the slides 47 whereby to accomplish bodily reciprocating movement of the hopper 41 which is supported on the slides 47 by means of the brackets 49. Inasmuch as the force of the arms 56 is first exerted in one direction or the other at the bottom portion of the hopper 41 and the hopper is rockably supported at its upper portion on the yokes 51, it will readily be seen that a tilting movement is first imparted to the hopper 41 before sliding movement is realized. In other words, at the rear end of a stroke the pins 57 are in abutment with the blocks 59 and before reversal of sliding movement can begin the pins must shift to engagement with the rear edges of the brackets 49. Similarly, at the forward end of a stroke the pins 57 must shift from the brackets 49 into abutment with the blocks 59. During this free shifting movement of the pins 57 it will be seen that the hopper 41 is tilted in the appropriate direction to obtain scraping engagement of the trailing bottom edge of the hopper opening with the stencil plate 37.

In order to insure proper tilting of the hopper 41 at the extreme end of each sliding stroke of the slides 47 and before movement in the reverse direction starts, I provide an adjustable braking mechanism to retard the sliding movement of the slides 47. This mechanism comprises an elongated friction member or shoe 61 slidably engaging the outer edge of one of the slides 47 and having a pair of outwardly extending guide pins 62. A coacting support 63 is rigidly mounted on the outer wall of the stencil box 37a by means of a pair of screws 64 and is spaced outwardly from the shoe 61. For urging the shoe 61 against the slide 47, a pair of spring members 66 bear against the shoe 61 and extend through suitable apertures 67 and aligned outwardly projecting tubular portions 68 on the support 63. Each tubular portion 68 is inter-

nally threaded and is fitted with a set screw 69 for adjusting the spring pressure and the degree of frictional contact of the shoe 61 with the slide 47. The guide pins 62 on the shoe 61 are slidably received in suitable apertures or bores 71 in the support 63. By this arrangement it will be understood that the spring pressed shoe 61 causes sufficient frictional drag on the movement of the slides 47 so that as soon as the direction of movement of the arms 56 is reversed, the 10 hopper 41 will tend to remain in its same position relative to the stencil box and will first undergo rocking movement before actual engagement of the pins 57 with the brackets 49 or the blocks 59 causes reverse sliding movement of the hopper.

This movement of the hopper 41 is clearly illustrated in Figs. 2 and 4 of the drawings. In Fig. 4 the hopper 41 is illustrated in the course of its movement from right to left with the lower edge of the right side wall 42 of the hopper being in line contact with the upper surface of the stencil plate 37 and with the lower edge of the left side wall 42 of the hopper 41 being in raised position. In Fig. 2 the hopper is shown as it appears at each end of its strokes but before it has been rocked for the return stroke. The hopper shown in full lines at the right still has the lower edge of its left side wall 42 in engagement with the upper surface of the stencil plate 37, this line contact having existed all the time the hopper was moving from the left position to the right position. However, as the arms 56 begin their movement to the left, the braking arrangement above described tends to resist movement of the slides 47 until the pins 57 shift out of engagement with the blocks 59 and into engagement with the brackets 49 thus causing the hopper to tilt relative to the upper surface of the stencil plate 37 so that the lower edge of the right side wall 42 will now be moved downwardly into scraping line contact with the stencil plate 37 and the lower edge of the left side wall 42 raised therefrom before the slides 47 start to move to the left.

Similarly when the hopper reaches the left hand position as shown in Fig. 2 and the slide begins its movement to the right, the pins 57 will first effect tilting of the hopper 41 in the opposite direction before direct engagement of the pins 57 with the blocks 59 causes sliding movement of the slides 47 in the opposite direction.

By means of this scraping or squeegeeing action of the trailing edge of the hopper in line contact with the stencil plate 37, the coating material within the hopper is confined between the flared bottoms of the side walls 42 during sliding movement thereof across the stencil plate 37 and also during the time when the hopper is rocked at the ends of its strokes. Because of the line contact between the trailing edge of the hopper and the stencil plate 37 none of the coating material is left behind on the stencil plate during sliding movement but is always forced ahead of the trailing edge. It is to be noted that because the advance edge of the hopper is raised from the stencil plate there is a space through which the coating material might pass were it not for the fact that the movement of the hopper is sufficiently rapid and the coating material is sufficiently plastic to prevent such leakage. The advance raised edge always remains ahead of the coating material which is forced down by a mechanism to be later described against the upper surface of the stencil plate 37 immediately inwardly of the ad-

vance edge. Thus when the hopper 41 is rocked and the other edge moves downwardly into contact with the stencil plate 37, no coating material is interposed therebetween. The engagement, therefore, between the hopper edges and the stencil plate is in most instances a clean line contact. However, in the event the viscosity of the coating material is of a lower degree so that it is somewhat more flowable to permit slight leakage ahead of the raised side wall of the hopper during sliding movement, nevertheless because of the line contact the edge of the hopper upon rocking movement will cut down through such coating material into intimate engagement with the stencil plate and wipe the plate clean on its return movement. It is thus apparent that by this novel form of hopper and hopper control mechanism the stencil box is kept relatively free of coating material and no large masses thereof are permitted to form at each end of the hopper stroke. Consequently, most or all of the coating material is forced down through the stencil openings 38 onto the wafers therebelow and the services of an operator in seeing that the stencil box is kept clean are dispensed with.

In order to raise the wafers 46 up against the under surface of the stencil plate 37 there is provided a channel-shaped member 72 which extends transversely of the machine beneath the belt 11, the upper edges of the channel member 72 being adapted to engage the under surface of the belt 11 at points spaced from either side of the wafers so as not to damage the same. The channel-shaped member 72, as shown in detail in my aforementioned copending application S. N. 47,463, is secured to slidable lifting rods (not shown) suitably supported on the frame of the machine and arranged for cam actuated operation in synchronization with movement of the hopper 41 so that the wafers 46 will be raised into position (Fig. 4) under the stencil plate 37 prior to the time the hopper 41 slides over the stencil plate to deposit a coating 44 simultaneously on each of the wafers.

After the coating 44 has been applied to the upper surfaces of the wafers, the coated wafers tend to adhere to the under surface of the stencil plate 37 due to the tackiness of the coating material. Provision is therefore made for releasing the coated wafers so they may be restored to position on the belt 11 as it is lowered for further intermittent movement. This releasing or stripping means comprises two sets of stripping or punch-out fingers 79 arranged in aligned groups on each side of the hopper 41 and adapted to be projected downwardly through the hopper openings 36 so as to push the coated wafers down away from the stencil plate 37. The sets of stripping fingers 79 are alternately operable after the hopper 41 has passed over the stencil plate openings 38 and is approaching the end of its stroke.

Each of the sets of stripping fingers 79 depends from a transversely extending bar 80 having upwardly turned ends at each side thereof secured to vertically slidable blocks 82 at each side of the hopper. The transversely opposed blocks 82 at each side of the machine are secured together by cross bars or braces 83 so as to operate in their vertical movements as a unit. Each of the blocks 82 is provided with a central opening through which extend vertically directed rods 84 secured to the upper surface of the slides 47. Projecting outwardly from each of the blocks 82 on each side of the machine is a roller 86 which is adapted to engage the upper surfaces of two inclined tracks

37 and 88 on each side of the machine secured on the guide members 45.

The stripper bars 89 are, therefore, adapted to be raised and lowered at appropriate times as the hopper moves from one side of the stencil plate to the other. Referring to Fig. 2 of the drawings, it will be seen that when the hopper 41 is in its right hand position on the stencil plate 37, the right hand stripper mechanism and its roller 86 is adjacent the upper right end of the trackway 88. As the hopper 41 moves to the left, the stripping mechanism is also carried to the left on the slides 47, the roller 86 rolling down the inclined track 88 to the lower end thereof. When this point is reached, the hopper has entirely passed over the stencil plate openings 38 and the coated wafer is ready to be released. Thus at this point the stripping fingers 79 are permitted to drop down through the stencil plate openings 38 with a sharp sudden movement so as to punch out the adhering wafers without separating the coating therefrom. This sudden dropping movement of the stripping fingers 79 is caused by the sudden dropping off of the rollers 86 from the trackway 88, the trackways 87 and 88 being spaced apart at their lower adjacent edges to permit the roller 86 to drop downwardly therebetween.

Similarly, when the hopper 41 is in its left hand position as shown in Fig. 2 by the broken lines, the stripper mechanism on the left side thereof is at the upper end of the inclined trackway 87, and as the hopper 41 is moved to the right, the stripping mechanism is gradually lowered until the roller 86 thereof suddenly drops off the lower end of the trackway 87, the coated wafers which were coated on the movement of the hopper from left to right thus being punched downwardly in similar manner.

Before the hopper 41 may commence its return stroke, it is necessary to elevate the stripping mechanism and the stripping fingers 79 from the stencil plate openings 38 and this is accomplished by vertical lift rods 89 on each side of the machine which are adapted to engage the rollers 86 of each of the stripping mechanisms. The lift rods 89, as disclosed in detail in my copending application S. N. 47,463, now U. S. Patent Number 2,563,813, are slidably supported on the frame of the machine and are cam actuated in synchronized operation with movement of the hopper 41 so as to lift the rollers 86 above the lower edges of either the trackways 87 or 88 just before the hopper 41 commences its return movement. The lift rods 89 thus serve to elevate at the proper times both the right and left stripper mechanisms.

In order that the coating material may be under constant feeding pressure within the hopper 41 as the hopper slides over the stencil plate openings 38, there is provided a vertically reciprocable pressure means 93, shown particularly in Figs. 2 and 3 of the drawings. This pressure means comprises an enlarged cylindrical bar 94 extending horizontally within the hopper between the side walls 43 thereof for movement downwardly from approximately the center line of the hopper. This enlarged pressure bar 94 is supported by spaced vertical bars 96 whose upper ends are in turn secured to a horizontal cross bar 97, the respective ends of which project beyond the end walls 43 of the hopper. These projecting ends of the cross bar 97 are provided with depending arms 98 and the lower ends of these depending arms are provided with oppositely directed slide bars 99 so as to form an inverted sloping T. The slide bars 99 are adapted to alternately engage the upper surfaces of the tracks 87 and 88 and they are of

sufficient length to bridge the gap between the tracks 87 and 88. The slide bars 99 are also angularly disposed with respect to the depending arms 98 so as to be in planes parallel to the tracks 87 and 88, respectively, thus facilitating sliding movement.

The vertical bars 96 of the pressure means 93 adjacent the end walls 43 of the hopper are slidably received in vertical channels 95 cut in the inner surface of the end walls 43 of the hopper so that the vertical movement of the pressure means 93 is guided thereby. Thus when the hopper is moved from one end of the stencil plate 37 toward the openings 38, the pressure bar 94 moves downwardly within the hopper exerting a pressure on the coating material below it, this lowering of the pressure bar 94 being permitted as the slide bars 99 slide downwardly on one of the inclined tracks 87 or 88, and the point of greatest pressure being directly over the center of the openings 38 in the stencil plate 37. As the hopper continues on toward the end of its stroke, the pressure bar is then raised as the bar 99 slides up the opposite track.

After the wafers 46 have been coated and released from the stencil plate 37 by the stripping mechanism, they continue intermittently onwardly on the belt 11 until they pass under another wafer magazine 100 (Fig. 1) also comprising a plurality of vertical chutes. These chutes are also filled with wafers which are fed onto the coating material 44 of the previously coated wafers by means of a slide 101 operably connected with the motor in a manner similar to first feeding mechanism 12, thereby forming a sandwich cookie.

Although there has been described above and illustrated in the drawings a preferred embodiment of a hopper and hopper control mechanism for a wafer coating machine, it is to be understood that changes and modifications may be made in the structural details and mode of operation thereof without departing from the spirit and scope of the appended claims.

I claim:

1. In a machine for coating cakes having a stencil plate with an opening therein and means for supporting a cake adjacent said opening, the combination comprising a hopper having opposed side walls and a bottom opening between said side walls and being adapted for tilting movement and for reciprocating sliding movement across said stencil plate in engagement therewith, a pair of elongated slides reciprocably mounted adjacent the lower portion of the hopper at the opposite ends thereof, upright hopper supports carried on said slides, vertically movable pivot means rockably supporting said hopper at the upper portion thereof on said supports, adjustable means coacting with said pivot means and with said supports for regulating the clearance between said hopper and said stencil plate, and actuating means operatively engaging said slides and said hopper at the lower portion of the latter for effecting tilting and reciprocation of the hopper, said hopper thereby being rockably mounted for tilting movement relative to said plate and the lower edge of only one side wall being adapted to be in scraping contact with said plate when the hopper is tilted in one direction and moved across said plate and the lower edge of only the other side wall being adapted to be in scraping contact with said plate when the hopper is tilted in the opposite direction and moved in the return direction across

11

the plate, and said adjustable means permitting control of the scraping pressure of the lower edges of the hopper side walls as the hopper moves across the stencil plate whereby to avoid excessive wear of the plate.

2. In a machine for coating cakes having a stencil plate with an opening therein and means for supporting a cake adjacent said opening, the combination comprising a hopper having opposed side walls and a bottom opening between said side walls and being adapted for tilting movement and for reciprocating sliding movement across said stencil plate in engagement therewith, reciprocating means for moving said hopper back and forth across said stencil plate including a pair of elongated members slidably mounted adjacent the lower portion of the hopper at the opposite ends thereof, upright bracket means rigidly carried on said slidable members, pivot pins extending outwardly from the ends of said hopper at the upper portion thereof, said pins being journaled in the upper ends of said bracket means for rockably supporting the hopper above said stencil plate, actuating means operatively connected to said hopper at the lower portion thereof for tilting the hopper about its pivotal mounting on said bracket means and also operatively coating with said elongated slidable members for reciprocating the latter, said hopper thereby being rockably mounted for tilting movement relative to said plate and the lower edge of only one side wall being adapted to be in scraping contact with said plate when the hopper is tilted in one direction and moved across said plate and the lower edge of only the other side wall being adapted to be in scraping contact with said plate when the hopper is tilted in the opposite direction and moved in the return direction across the plate, and adjusting screw means coacting with said bracket means and said pivot pins for regulating the clearance of said hopper above said stencil plate whereby to control the scraping pressure of the lower edges of the hopper side walls as the hopper moves across the plate.

3. In a machine for coating cakes having a stencil plate with an opening therein and means for supporting a cake adjacent said opening, the combination comprising a hopper having opposed side walls and a bottom opening between said side walls and being adapted for tilting movement and for reciprocating sliding movement across said stencil plate in engagement therewith, a pair of elongated slides reciprocably mounted adjacent the lower portion of the hopper at the opposite ends thereof, a pair of upright brackets rigidly carried on said slides, a pair of abutments rigidly carried on said slides and longitudinally spaced from said brackets, means for pivotally supporting said hopper at the upper portion thereof on said brackets, stud means extending rigidly at opposite ends of the lower portion of the hopper intermediate said brackets and said abutments for coaction therewith, and reciprocal actuating means connected to said stud means for effecting tilting of the hopper and reciprocation of said slides, said hopper thereby being rockably mounted for tilting movement relative to said plate and the lower edge of only one side wall being adapted to be in scraping contact with said plate when the hopper is tilted in one direction and moved across said plate and the lower edge of only the other side wall being adapted to be in scraping contact with said plate when the hopper is tilted in the opposite direction and moved in the return direction across the plate.

12

hopper is tilted in the opposite direction and moved in the return direction across the plate.

4. In a machine for coating cakes having a stencil plate with an opening therein and means for supporting a cake adjacent said opening, the combination comprising a hopper having opposed side walls and a bottom opening between said side walls and being adapted for tilting movement and for reciprocating sliding movement across said stencil plate in engagement therewith, a pair of elongated slides reciprocably mounted adjacent the lower portion of the hopper at the opposite ends thereof, a pair of upright brackets rigidly carried on said slides, means pivotally supporting said hopper at the upper portion thereof on said brackets whereby to permit swinging movement of the lower end of said hopper, a pair of rigid abutments on said slides spaced from said brackets, a pair of studs extending rigidly from the lower portion of said hopper in between said brackets and said abutments, said studs being adapted to undergo limited movement between said brackets and said abutments for tilting the hopper about its upper pivotal support and said studs also being adapted to undergo alternate operative engagement with said brackets and said abutments for shifting said slides in opposite directions, and reciprocating actuating means operably connected to said studs for effecting said tilting and shifting movements, said hopper thereby being rockably mounted for tilting movement relative to said plate and the lower edge of only one side wall being adapted to be in scraping contact with said plate when the hopper is tilted in one direction and moved across said plate and the lower edge of only the other side wall being adapted to be in scraping contact with said plate when the hopper is tilted in the opposite direction and moved in the return direction across the plate.

5. In a machine for coating cakes having a stencil plate with an opening therein and means for supporting a cake adjacent said opening, the combination comprising a hopper having opposed side walls and a bottom opening between said side walls and being adapted for tilting movement and for reciprocating sliding movement across said stencil plate in engagement therewith, a pair of elongated slides reciprocably mounted adjacent the lower portion of the hopper at the opposite ends thereof, upright bracket means rigidly carried on said slides and pivotally supporting said hopper at the upper portion thereof, abutment means carried on said slides in spaced relation from said bracket means, a pair of elements projecting rigidly from the lower portion of said hopper between said bracket means and said abutment means on the respective slides for coaction alternately with said bracket means and with said abutment means, reciprocal actuating means operatively connected to the lower portion of said hopper for tilting the latter about its upper pivotal mounting whereby said projecting elements are also engaged alternately with said bracket means and with said abutment means for shifting the slides in alternate directions, said hopper thereby being rockably mounted for tilting movement relative to said plate and the lower edge of only one side wall being adapted to be in scraping contact with said plate when the hopper is tilted in one direction and moved across said plate and the lower edge of only the other side wall being adapted to be in scraping contact with said plate when the hopper is tilted in the opposite direction and moved in the return direction across the plate.

13

direction across the plate, and adjustable brake means coacting with at least one of said slides for retarding reciprocating movement thereof whereby to insure tilting movement of said hopper prior to each reversal of direction of said slides.

6. The apparatus described in claim 4 further characterized in that at least one of said slides is provided with an adjustable spring pressed brake shoe adapted to exert a predetermined frictional drag on said slides whereby to insure reverse movement of said studs and tilting of said hopper

14

before said slides are reciprocated in a reverse direction at the end of a stroke in any one direction.
